(57) **CLAIM**

The ornamental design for a communication device, as shown and described.

DESCRIPTION

FIG. 1 is a first perspective view of a communication device; FIG. 2 is a second perspective view of the device shown in FIG. 1;

FIG. 3 is a rear view of the device shown in FIG. 1;

FIG. 4 is a front view of the device shown in FIG. 1;

FIG. 5 is a right side view of the device shown in FIG. 1;

FIG. 6 is a left side view of the device shown in FIG. 1;

FIG. 7 is a top view of the device shown in FIG. 1; and,

FIG. 8 is a bottom view of the device shown in FIG. 1.

The broken lines immediately adjacent the shaded areas represent the bounds of the claimed design while all other broken lines are directed to environment and are for illustrative purposes only; the broken lines form no part of the claimed design.

1 Claim, 6 Drawing Sheets
